GUIDING DEVICE FOR SEWING MACHINES

Louis Margand, Paris, France, assignor to
Lucien Braun, Paris, France

Application May 29, 1950, Serial No. 164,951

Claims priority, application France June 16, 1949

1 Claim. (Cl. 112—151)

1

The invention has for its object a device which may be used in sewing machines in order to facilitate the execution of a stitching line which is to be made at a constant distance from a line existing on the material and taken as base line.

This device comprises a support rod adapted to be fastened on the bar of the presser-foot and carrying a split sleeve to which is secured to an arm, the free end of which is provided with an index blade, adapted to be applied on the base line hereinbefore mentioned.

The split sleeve may be fixed on the support rod at a smaller or greater distance from the bar of the presser-foot, according to the spacing length which is desired between the stitching line and the base line.

During stitching, the operator has only to maintain the index blade in contact with the base line, and thus the line of stitching made by the needle is at a constant distance from the base line.

The annexed drawings show by way of example a device in conformity with the invention.

Fig. 1 is an elevation view showing a sewing machine provided with a guiding device according to the invention, the needle and the needle bar having been omitted.

Fig. 2 is an elevation view of the guiding device.

Fig. 3 is a sectional view taken on line III—III of Fig. 2.

Fig. 4 is a plan-view corresponding with Fig. 2, 30 the needle and needle-bar having been removed and the presser bar being shown in section.

Figs. 5 and 6 are elevation views taken from the left and from the right of Fig. 4 respectively. Fig. 7 is an elevation view corresponding with Fig. 6 but showing the index blade and its arm in a raised inoperative position.

In the drawings, 1 is the frame of an ordinary sewing machine, 2 the presser-foot fixed on a bar 3 by means of a screw 4, 5 the needle fastened on the needle bar by means of a needle holder 7 provided with a screw 11.

According to the invention, the bar 3 of the presser-foot 2 carries a collar 8 provided with clamping screws 9 and 10 which fasten the said collar on the bar.

The collar 8 is integral with a prismatic block 12 in which a horizontal rod 13 is pivoted. This rod carries a split sleeve 14, both jaws of which may be clamped by means of a screw 15 so as to 50 fasten the sleeve 14 on the rod 13 at a suitable distance from the block 12.

The sleeve 14 has a transverse bore in which the rectilinear end of an arm 16 is engaged. This arm carries an index blade 17 which may be laid 55

2

on the material to be sewn. The shape of the arm 16 is such that the said arm cannot meet the needle holder 7 or its screw 11, even if the sleeve 14 is near the block 12. The arm 16 is fixed in the sleeve 14 by means of a screw 18.

The rod 13 carries a ring 19 fastened by means of a screw 21. This ring has two rectilinear grooved flat portions which are perpendicular to each other. A spring 22 fastened by means of a screw 23 on the block 12 has a bead on its free end which engages in one or the other of the grooves of the ring 19 according as the arm 16 is lowered or raised.

The block 12 may be preferably provided with a thread cutter 24.

The operation of the device is as follows:

The screw 15 being loosened, the sleeve 14 is brought to a suitable distance from the block 12, this distance being greater or smaller, according 20 to the spacing which is desired between the stitching line to be made and the base line to which the said stitching line must be parallel. The screw 15 is then tightened so as to fasten the sleeve 14 on the rod 13.

According to the thickness of the material, the arm 16 may be slightly displaced in the sleeve 14 after loosening of screw 18, and then the said screw is tightened again.

After each member of the device is in the proper position, the material is positioned so as to bring the index blade 17 on the base line chosen (former stitching line, stripe, edge, or the like), then the sewing machine is started and the material is pushed forward under the presser-foot, while the base line is still maintained under the index blade 17. The stitching line obtained is thus exactly parallel to the base line.

It is to be observed that the rod 13 is in a symmetrical position relatively to the frame 1 and the operator is in no way troubled by any projecting member.

Due to this device, right or curve stitching lines may be executed with accuracy and rapidity, at a desired distance from the edge of the material or from any line, so small this distance may be.

When the guiding device is not in use, the arm 16 may be raised as shown on Fig. 7. In that movement, the ring 19 rotates by 90 degrees, while the spring 22 passes from one groove of the ring to the other one, and maintains the arm 16 in the raised position. The arm and its index blade 17 do not in the least hinder the work to be performed later when the guide is not used.

The mounting and removing of the device are

instantaneous and no tool but a screw-driver is necessary.

The device having been adjusted for a work, if it is desired, after execution of this work, to keep the adjustment in order to later make the same work, it is possible to remove the rod 13 with the ring 18, the sleeve 14 and the arm 16 all in the positions that they occupy on said rod simply by pulling the rod 13 with its assemblages from the bore in block 12, the beaded end of spring 22 snapping from groove 19 upon applying sufficient pulling force to the rod 13. Before the rod 13 and its assemblage is used again, another rod 13 and a set of similar members may be put on the machine.

Obviously the invention is not restricted to the form of construction represented in the drawings, this form being given only as an example and any change of construction may be adopted without exceeding the scope of the invention.

I claim:

A stitching guide for a sewing machine having a vertical presser foot bar comprising a support block secured to the vertical bar of the presser foot and having a horizontal bore therein, a support rod having a cylindrical extremity axially slidably and rotatably mounted in the bore of the support block, a guide plate carried

by the support rod, a ring fixed to the rod between the guide plate and the cylindrical extremity, said ring having two adjacent flat surfaces on the circumference thereof substantially perpendicular to each other, a peripherally extending groove in each of said flat surfaces, a leaf spring having one end fixed to said support block and having a free end provided with a curved lug-like portion, extending beyond the block to a position to engage in one of said grooves of the ring when the rod is in the bore of the block, said spring being tensioned to cause the lug-like portion to releasably resiliently enter into one of said grooves, to releasably retain the rod against axial movement in the bore of said block and to releasably retain the rod against rotary movement in said bore.

LOUIS MARGAND.
